(57) **CLAIM**

(22) Filed: **Nov. 6, 2001**

The ornamental design for an electronic sound recording and
reproducing device for a baby, as shown.

(30) **Foreign Application Priority Data**

DESCRIPTION

May 29, 2001 (XH) DMA/005 325

FIG. 1 is a perspective view showing my design;

(51) LOC (7) Cl. **14-01**

FIG. 2 is a front elevational view thereof;

(52) U.S. Cl. **D14/167**; D14/192; D14/159;

FIG. 3 is a rear elevational view thereof;

D10/104

FIG. 4 is a right side elevational view thereof;

(58) **Field of Search** D3/218; D10/104,

FIG. 5 is a left side elevational view thereof;

D10/106, 116, 121; D14/159, 167-168,
192; D11/79-80; 340/345, 348-351, 354,

FIG. 6 is a top plan view thereof; and,

371-374, 571-573

FIG. 7 is a bottom plan view thereof.
